United States Patent Office.

WILLIAM H. PILGRIM, OF ALLEGHENY CITY, PENNSYLVANIA.

Letters Patent No. 94,768, dated September 14, 1869.

IMPROVED SASH-BALANCE.

The Schedule referred to in these Letters Patent and making part of the same.

To all whom it may concern:

Be it known that I, WILLIAM H. PILGRIM, of the city and county of Allegheny, and State of Pennsylvania, have invented a new and useful Improvement in Suspending Window-Sash; and I do hereby declare that the following is a full, clear, and exact description thereof, reference being had to the accompanying drawings, and to the letters of reference marked thereon.

The nature of my invention consists in suspending the sash of windows, through the media of cords, pulleys, and cams inserted in the frame, all constructed, arranged, and operating so that the cords are hidden in the frame, substantially as hereinafter described.

To enable others skilled in the art to make and use my invention, I will proceed to describe its construction and operation.

In the accompanying drawings, which form part of my specification—

Figure 1 is a front elevation of a window-frame and its sash provided with my improvement for suspending the sash.

Figure 2 is a transverse section of the same, when cut through at line *y*. of fig. 1.

Figure 3 is a front elevation of the window-frame and its sash, representing the upper part of the sash lowered, and the lower part of the sash raised.

Figure 4 is a vertical section of the cam and its frame, used for holding the sash-cord in the desired position for holding the sash, when either part is raised or lowered.

In the accompanying drawings—

A represents the window-frame.

B represents the upper part, and *C*, the lower part of the window-sash.

The frame and its sash are constructed in the ordinary manner.

In the upper part of the frame *A*, and on a line with the outer edges of the sash, are pivoted "grooved pulleys" *e*, and in the lower part, *C*, of the sash are fitted frames *f*, in which are pivoted cams *g*, as shown in fig. 4.

The frames *f* are fitted in openings, which run in an oblique line from the edge to the front or face of the sash, as shown in figs. 1 and 2.

The cords *D* are secured to the upper part *B* of the sash, and pass up and over the pulleys *e*, and down and through the cam-frames *f*, as shown in fig. 4.

On the outer end of the cords *D* are loops *x*, which are looped over knobs *i*, secured on the face of sash *C*.

As the construction and arrangement of the several parts, and the relation they bear to each other, will be readily understood from the foregoing description, and by reference to the accompanying drawings, I will therefore proceed to describe the operation of my improvement, which is as follows:

By drawing on the outer ends of the cords *D*, the part *C* of the sash will be raised, and the cam *g* will hold the cords when the sash is raised to the desired height. By raising the lower sash *C* without drawing on the cords *D*, the upper sash *B* will be lowered equal to the rise of sash *C*.

I wish it clearly understood that I am aware that window-sashes have been suspended by means of cords, pulleys, and cams, therefore I do not claim, broadly, their use for suspending sashes. The novelty of my improvement consists in so arranging the cords, pulleys, and cams as that they are hidden in the frame of the window and its sash.

Having thus described the nature, construction, and operation of my improvement,

What I claim as of my invention, is—

Suspending window-sash, through the media of cords *D*, pulleys *e*, and cams *g*, inserted in the frame, all constructed, arranged, and operating so that the cords are hidden in the frame, substantially as herein described, and for the purpose set forth.

W. H. PILGRIM.
